UNITED STATES PATENT OFFICE.

VICTOR M. WEAVER, OF HARRISBURG, PENNSYLVANIA, ASSIGNOR TO WEAVER COMPANY, A CORPORATION OF WISCONSIN.

ELECTROLYTIC APPARATUS.

1,329,315.

Specification of Letters Patent.

Patented Jan. 27, 1920.

Original application filed August 22, 1914, Serial No. 858,001. Divided and application filed January 11, 1915, Serial No. 286. Divided and this application filed July 9, 1915. Serial No. 38,858.

To all whom it may concern:

Be it known that I, VICTOR M. WEAVER, a citizen of the United States, residing at Harrisburg, in the county of Dauphin and State of Pennsylvania, have invented a certain new and useful Improvement in Electrolytic Apparatus, of which the following is a full, clear, concise, and exact description, reference being had to the accompanying drawings, forming a part of this specification.

My invention relates to apparatus for carrying out electrolytic processes and steps in processes and contemplates a generally simplified and efficient structure wherein the action may effectively be carried on. One important feature of my invention lies in the means for feeding the material to be treated to the compartment wherein the electrolytic work is accomplished and by this means I am enabled to carry out certain processes more effectively and to carry out processes which heretofore have not been possible. Other features of my invention are concerned with the construction of certain parts and the arrangement of the elements. A further feature of my invention lies in the sealed construction which I provide for purposes hereinafter pointed out.

It will be clear to those skilled in the art that my invention will admit of broader application than the specific uses which I shall describe as an instance of its employment. In order to simplify this description I shall describe my apparatus as employed in carrying out a process of securing aluminum from aluminum chlorid.

This application is divisional from my co-pending application, Serial No. 286 filed January 11, 1915, which in turn is divisional from my co-pending application, Serial No. 858,001, filed August 22, 1914, which is concerned with a process and apparatus for winning metals and which, in its more specific aspects, relates to the treatment of clay in order to secure the aluminum and the silicon therefrom.

In order to instruct those skilled in the art, I shall now proceed with a specific description of my invention as utilized in my process of securing aluminum and silicon

from clay, and shall refer to and describe the various parts of the apparatus and the various stages in the process in detail, in order that I may make a complete and intelligent disclosure.

In the treatment of clay, I break up the compound by the use of chlorin gas so as to produce aluminum chlorid and silicon tetrachlorid, this action being carried on under special restrictions and conditions, as will later be more fully described. With the aluminum chlorid thus produced, the next step, so far as this particular part of the process is concerned, is to secure the aluminum therefrom and this I carry out by electrolysis under certain conditions and restrictions calculated to effect an advantageous and continuous process. I charge the aluminum chlorid into an electrolyzing bath preferably containing melted sodium chlorid, and the consequent electrolysis separates the aluminum from the chlorin, so that the former may be tapped away from the sodium chlorid, while the latter may be conducted to a storage tank for further use. It is important in this connection that in carrying out my process I keep the electrolytic bath saturated by steady, regulated additions of aluminum chlorid, and this proves to be a feature of 80 distinct advantage and paramount importance.

My invention will be more readily understood by reference to the accompanying drawings, in which:

Figure 1 is a more or less diagrammatic representation of the entire system of apparatus.

Fig. 2 is a sectional view, taken on a horizontal plane, of the electrolyzing vat.

Figs. 3 and 4 are other sectional views.

Referring first to Fig. 1, it will be seen that the chlorinizing furnace is shown at 9. The details of this furnace are unimportant in connection with the present application and it suffices to say that a charge is introduced into the chlorinizing furnace, which is preferably heated by electrical means. A pipe 30, which comes from a storage tank 31, is led into the chlorinizing furnace, as indicated in the drawing, and

in this way the charge in the furnace is treated with chlorin gas from the storage tank 31, the connection being controlled by a valve 32. Assuming that the charge in the furnace is bauxite or of one of the higher grades of clay, such as kaolin, I treat this charge with the chlorin gas in the presence of carbon. With the current properly applied to the furnace electrodes, the activity of the chlorin gas and the heat immediately effects the disintegration of the kaolin, the formation of aluminum chlorid and silicon tetrachlorid, and, by the combination of the carbon and the oxygen liberated from the kaolin, the formation of carbon monoxid.

The three gases thus formed naturally arise and pass out of the chlorinizing furnace 9 and are conducted to a condenser 33. This condenser is in the form of a double closed chamber providing the compartment 34 and the compartment 35, separated by a partition 36. The compartment 34 is provided with a system of cooling pipes 37, 37, which extend downwardly through and from the top of the chamber and which are distributed throughout the entire space of this particular compartment in order to get a complete temperature control. The pipes 37, 37 are joined at the upper end, outside of the chamber, by means of the header pipe 38, and circulation is secured in any desirable manner. In this particular condenser element the system of pipes is connected to a cold water supply and the result is that as the three gases which have been referred to enter and pass through the compartment 34 the aluminum chlorid gas, which condenses at a higher temperature than the silicon tetrachlorid gas, is condensed and deposits itself as a white powder upon the pipes 37, 37.

Since the temperature which is produced by the circulation of mere cold water in the cooling pipes 37, 37, is not sufficiently low to condense silicon tetrachlorid, this gas, together with the carbon monoxid, passes on to the next compartment 35 of the condenser. Thus the first condenser element 34 is devoted to the condensation of the aluminum chlorid, and the white powder to which it is reduced is removed from the pipes upon which it is deposited by means of the scrapers 39, 39. The powder is thus thrown down on to the conveyer 42 and carried to a tank 45, the connection to which is controlled by a valve 46. It will be seen that this tank is connected by means of a pipe 47, with a compressed air tank 48, which is fed through the air compressor 49. It is important, as before indicated, that the system be a closed system and that various actions be carried on under pressure, and I speak of it particularly at this time because of the fact that the aluminum chlorid to which I

have just referred is extremely deliquescent and must be kept free from moisture in order to avoid decomposition and the formation of hydrochloric acid. When the system is closed, however, such a result is not possible, and the inclosure is effective in condensing and keeping condensed this volatile substance.

Leaving the aluminum chlorid, which has been deposited in the tank 45, for the present, I shall follow the course of the silicon tetrachlorid gas and the carbon monoxid through the second element of the condenser. The condenser element 35 is provided with a system of cooling pipes 50 like the pipes 37, 80 these pipes having the outside header 51 and being provided with scrapers 52, 52. Instead of being supplied with mere cold water, however, the cooling pipes 50 are supplied with a freezing mixture of ice water and salt, and the temperature in the condenser element 35 is therefore considerably lower than the temperature in the condenser element 34. The lower temperature is sufficient to condense the silicon tetrachlorid, which comes down as a colorless liquid, except for any impurities which may discolor it. This liquid silicon tetrachlorid passes down the sloping bottom of the condenser element 35 and passes through the outlet 55, controlled by the valve 56, which leads to the tank 57. The tank 57 has an outlet pipe 57.

The carbon monoxid passes out of the condenser element 35 through a pipe 59, past a valve 60, into a closed gas pump 61, and is then carried to a scrubber 62 by means of a pipe 63, this scrubber being in the form of a tank containing lime water and having an outlet pipe 63' leading therefrom. This outlet pipe is provided with a valve 64 and leads to a telescoping gas tank 65, so that pressure may be kept upon the carbon monoxid which finds its way to this tank, and so that the carbon monoxid may be fed by way of a pipe 66 to any number of burners 67, 68 and 69, which are used for heating purposes in certain other steps of the process which will hereinafter be referred to.

Where additional chlorids are formed in the chlorinizing furnace, which condense at other temperatures, as is the case when iron or titanium is present in clay, the condenser may be arranged to separate these from the aluminum and silicon chlorids and from each other if desired, by increasing the number of elements maintained at different temperatures required to separately deposit the substances.

Returning now to the aluminum chlorid which has been deposited in the form of a powder in the tank 45 (this powder being white unless discolored by impurities) it will be noted that I have placed the burner 67 under this tank, and I may mention here

that I surround the tank with a suitable fire wall so that I can subject the tank to a high degree of heat. With the valve 46 closed, the material in the tank 45 can be placed 5 under high pressure from the tank 48, and this pressure prevents the aluminum chlorid, melted by heat from the carbon monoxid burner, from vaporizing. Once in this condition the aluminum chlorid is much more 10 stable and much more easily handled, due to its physical condition, and desirably so in view of the steps which are to follow and which will presently be described. I desire 15 to state, however, that it is entirely feasible 20 to conduct the aluminum chlorid to the farther parts of the system in its dry, infused state, and I therefore do not wish to be limited to the inclusion of this step of melting the aluminum chlorid.

A pipe 70 leads from the tank 45 to a valve 71, which in turn is connected with a pipe 72 leading into a furnace, preferably of the Rodenhauser three-phase type. This furnace 25 comprises a heavy outer housing which is provided with a round bottom 74 mounted in a correspondingly shaped base 75, the idea being that when the connecting pipes are temporarily detached, the furnace can be tilted in order to tap off molten 30 metal, as will be pointed out a little later. The lining of the furnace provides a cavity for the molten metal which is formed between and around tubular casing parts within 35 which the magnetic circuit frame and the primary coils are disposed. The details of this furnace do not constitute part of my present invention, but I refer to them because it is a type of furnace well adapted 40 for use as part of my system. It will be seen that when the valve 71 is opened the liquid aluminum chlorid is conducted to the working chamber of the Rodenhauser furnace. The reason for this step in the process is as follows:

In the first condensation of the aluminum chlorid in the condenser element 34, there are likely to be impurities, principally iron, and it is the object of the step in the process now under description to eliminate 50 this iron and to secure pure aluminum chlorid. Therefore, preliminarily, the Rodenhauser furnace is charged with aluminum, and the molten bath, as illustrated, is formed when as before stated, the valve 55 71 is opened and the liquid aluminum chlorid is fed into this bath of molten aluminum near the bottom thereof, the aluminum chlorid is immediately reconverted into a gas due to the release of pressure and 60 heat of bath, and passes up through the molten aluminum. Due to the greater affinity of the chlorin for the aluminum than for the iron, or other impurity for that matter, the chlorin releases the iron and 65 takes on the proper share of aluminum.

The result is that the refined aluminum chlorid will leave the bath of aluminum and will pass out of the furnace through the pipe 81. It will be noted that the pipe 81 divides into the pipes 82 and 83, which 70 are provided with valves 84 and 85, respectively. If the refined aluminum chlorid is to be further purified, the valve 84 is kept closed and the valve 85 is opened, so that the aluminum chlorid gas may pass 75 up the pipe 83 and be passed back into the condenser element 34 for condensation purposes, and in its refined state it will be recharged into the Rodenhauser furnace, as has been described, and this process may 80 be repeated until the required degree of purity has been obtained. At this point the valve 85 is closed and the valve 84 is opened, so that the substantially pure aluminum chlorid may be passed into what may 85 be termed "condenser #2," as indicated. This condenser is of the same structure as the condenser element 34, and the condensed aluminum chlorid in the form of a white powder is brought down into the tank 86. 90 In this tank 86 the aluminum chlorid may be put under pressure by way of the pipe 87 leading from the compressed-air tank 48, and may also be subjected to heat from a flame at the burner 69, preferably 95 confined within fire walls. This again melts the aluminum chlorid, which may then be conducted to a storage tank 88 through a pipe 89 controlled by a valve 90, the pure aluminum chlorid being kept under the 100 pressure transmitted from the tank 86 and being heated by a carbon monoxid flame at the burner 68 so as to be kept in a liquid condition.

From this storage tank 88 the liquid aluminum chlorid is conducted through a valve 91 and a pipe 92 to the electrolytic vat, which is also sealed, so that the aluminum chlorid may be kept in its liquid condition. This liquid condition is maintained by the 110 heat which is developed by the electrolytic action. The electrolytic vat is illustrated in detail in Figs. 2, 3 and 4 and it will be seen that it comprises a graphite hearth 93 and firebrick surrounding walls 94, 94, 115 with magnesite linings 95, 95, the entire vat being surrounded by sustaining plates 96. Along opposite sides of the vat are access openings 97, 97, which are normally sealed by means of covers 98, 98, and a tap 120 hole 99 is provided for a purpose that will be referred to presently, this tap hole being normally closed by means of the plug 100. A chlorin exit 101 is provided, and, as indicated in Fig. 1, this exit is connected 125 by means of a pipe 102, in which there is a valve 103, with a chlorin compressor 104, which in turn is connected by a pipe 105 with a chlorin cooler 106, these two elements being merely diagrammatically 130

4
shown. The cooler 106 is connected by means of a pipe 107 with the liquid chlorin tank 31, which has already been referred to, and the connecting pipe 107 is provided with a valve 108.

Returning to the detailed showing of the electrolytic vat, it will be seen from Figs. 3 and 4 particularly, that the anodes are in the form of graphite blocks 109, to each of which three stems 110, 110, are secured, the stems being firmly lodged in a reinforced firebrick seal cover 111. Each of the anodes is provided with a collar 112, which is engaged by a loose collar 113 which may be moved up and down by means of nuts 114 on bolt rods 115 extending upwardly from a packing-box cover 116, which surrounds the electrode stem and packs it at 117. By this arrangement the anode stems may be adjusted vertically so that the proper over-all adjustment may be secured within the vat. Copper bus bars 118, 118, connect the tops of the electrode stems 110, and in this way the current is conveyed to the bath, the graphite hearth acting as the opposite electrode. The center one of each set of three anode stems is drilled axially, as indicated at 110, and this bore is connected to distributing passageways 120, 120 in the corresponding graphite block. Each of these bores is connected by means of a pipe 121 with the supply pipe 92, which has been hereinbefore referred to, and a valve 122 is disposed in each pipe 121 and is intermittently operated for feeding purposes by a traveler 123 which is mounted upon a rotating shaft 124. Thus, when the various rotating shafts 124 are put into operation, and, as before stated, the valve 91 is opened to permit the passage of the liquid aluminum chlorid, a constant feed per unit of time is afforded down through the passageways 119 and into the vat.

The liquid aluminum chlorid is kept at a high temperature, about 200 degrees centigrade, and at about a pressure of two and a half atmospheres. The heating of the storage tank is transmitted to hot-oil baths in pipes 125 which surround the supply pipes 92, and thus it is insured that the aluminum chlorid be fed into the vat at the proper temperature. The electrolyte is a bath of melted sodium chlorid at a high temperature which is primarily induced by external means, but which is maintained by the application of the current. The aluminum chlorid is fed to the bath at such a rate as to keep the bath saturated. The action which takes place in the electrolytic vat separates the aluminum from the chlorin and leaves the sodium chlorid. Due to the difference in specific gravity between the pure aluminum which is thus obtained and the melted sodium chlorid, it is a simple matter to tap off the molten aluminum

by removing the plug 100, and in this way the first ultimate object of my process is obtained—the securing of aluminum in its elemental state from clay. Since the action is secured leaving sodium chlorid, the electrolyte may go on indefinitely. The chlorin which is freed is passed to the chlorin compressor 104, then to the cooler and then to the storage tank, where it is drawn from to supply the chlorinating furnace 9, all as hereinbefore described.

It will be seen that the process is uniquely continuous, and that the chlorin which is freed in the electrolytic vat may be used over and over again in the chlorinating furnace, while the carbon monoxid which is formed by the oxygen liberated from the clay and the coke which is introduced is used for burner purposes. It is important that the system be a closed system, as described, to exclude the moisture and to protect the active chlorids, particularly the aluminum chlorid.

An important feature in the matter of the operation of my system is found in the feeding of the melted aluminum chlorid, or aluminum chlorid in powdered condition for that matter, to the electrolytic vat. It is of importance that the electrolytic bath is fed with the aluminum chlorid in such a way as to keep the bath saturated.

It will be apparent to those skilled in the art that various modifications might be made in this system without departing from the spirit or scope thereof. For instance, one might use a different electrolyte. In heating the pipes which maintain the aluminum chlorid in its melted condition while being fed to the electrolytic bath, it might be better practice in some instances to use electric heating coils than to use an oil bath, and it might be well to heat the aluminum chlorid containers in a manner other than by the carbon monoxid flame. With the closed system which has been described, I have the particular advantage that there is no electrode consumption, and therefore when the electrodes are adjusted they will remain adjusted, and economic service is secured.

Referring to the electrolytic vat, I may mention here that the hearth is the cathode and the graphite blocks constitute the anode. The aluminum forms globules varying in size from mere specks to considerably larger particles, and they occur near the bottom and finally rest upon the bottom. The chlorin is liberated and streams away with great rapidity. The aluminum which is thus formed is heavier and settles to the bottom, and the particles of aluminum as formed above the bottom frequently join to form larger particles. As the process continues, the bottom is covered by melted aluminum, which, as described, is tapped out from the

vat. It is convenient to retain sufficient molten aluminum in the vat to keep the carbon cathode constantly covered.

It will appear that changes and modifications in the apparatus of my invention will be possible without departing from the spirit and scope of my invention. I have already referred to the fact that the apparatus of my invention has much wider application than for carrying out merely the process which I have cited as an instance of use, and it is to be understood that I contemplate any use to which my apparatus may be put. I desire, therefore, that the metes and bounds of my invention shall be determined by the appended claims, which I have drawn variously so as to bring out the combinations which, of themselves, and regardless of their use, are new.

20 I claim:

1. Apparatus for treating chlorid which comprises a closed chamber for containing an electrolyte having a graphite interior bottom as one electrode and a graphite block depending from a sealed cover as the opposite electrode, and means for feeding material into said electrolyte at a definite and controllable rate of speed.

2. Apparatus for treating chlorid which comprises a closed chamber for containing an electrolyte having a graphite interior bottom as one electrode and a graphite block depending from a sealed cover as the opposite electrode, and means for feeding material into said electrolyte through a bore in said block at a definite and controllable rate of speed.

3. In combination, a chamber having a common electrode at the bottom thereof, a plurality of electrode members extending vertically into said chamber, and a plurality of horizontal electrode members each common to a plurality of said first-named members and connected thereto at the bottom thereof in horizontal position, being spaced properly away from said first-named electrode.

4. In combination, a chamber having a graphite bottom for one electrode and adapted to contain an electrolyte, a cover sealing said chamber, an electrode passing through said cover, and means for adjusting the vertical position of said electrode, said elec-

trode having a passageway therethrough whereby said electrolyte may be fed with 55 non-gaseous material to be treated below the level thereof.

5. In combination, a closed chamber having an electrode at the bottom thereof, a plurality of electrode members extending vertically into said chamber, and a horizontal electrode member common to said first-named members and connected thereto at the bottom thereof in horizontal position, being spaced properly away from said first-named 60 electrode, said electrode members having passageways therethrough whereby said chamber may be fed with material to be treated.

6. In combination, a chamber having an 70 electrode block in the bottom thereof, a plurality of horizontal opposing electrode members disposed in said chamber, substantially parallel to said block, a plurality of vertical electrodes extending upwardly 75 from each of said horizontal electrodes, one of each of said plurality of vertical electrodes having a passageway therethrough, each said passageway being supplemented by diverging branches in the corresponding 80 horizontal member.

7. Apparatus for treating chlorid which comprises a closed chamber adapted to contain an electrolyte having a conducting interior bottom as one electrode and a conducting block depending from a sealed cover 85 as the opposite electrode, and means for mechanically feeding non-gaseous material into said electrolyte at a definite and controllable rate of speed.

8. In combination, a chamber adapted to contain an electrolyte, electrodes therein, and means for feeding non-gaseous material to be treated to said chamber by a plurality of paths to distribute the feed uniformly 95 throughout the electrolyte.

9. In combination, a chamber adapted to contain an electrolyte, electrodes therein, and means for feeding non-gaseous material to be treated to said chamber by a plurality 60 of paths in substantially uniform relation to the electrodes.

In witness whereof, I hereunto subscribe my name this 2nd day of July, A. D. 1915.

VICTOR M. WEAVER.
